DESIGN FOR A SHOE

Wallace H. Benton, Portsmouth, Ohio, assignor
to The Selby Shoe Co., Portsmouth, Ohio, a
corporation of Ohio

Application January 28, 1938, Serial No. 74,617

Term of patent 7 years

To all whom it may concern:

Be it known that I, Wallace H. Benton, a citizen of the United States, residing at Portsmouth, in the county of Scioto and State of Ohio, have invented a new, original, and ornamental Design for Shoes, of which the following is a specification, reference being had to the accompanying drawing, forming a part thereof.

Figure 1 is a side elevation of a shoe showing my new design.

Figure 2 is a perspective view of the opposite side of the shoe shown in Figure 1; and

Figure 3 is a fragmentary top plan view of the toe portion of the shoe. A particular feature of my design is the colored beading between the upper and sole portions of the shoe.

I claim:

The ornamental design for a shoe, substantially as shown and described.

WALLACE H. BENTON.
